[57] ABSTRACT

In an aqueous composition for dyeing human hair comprising an oxidation dyestuffs combination of a

wherein R is selected from the group consisting of $-\text{NH}-\text{CO}-\text{R}_1$, $-\text{NH}-\text{CO}-\text{NH}-\text{R}_1$ and $-\text{N}-\text{H}-\text{CS}-\text{NH}-\text{R}_1$ wherein R_1 is selected from the group consisting of a hydrocarbon radical with 1 to 12 carbon atoms and a heterocyclic radical, and (b) from 0.3 to 5 percent by weight of said composition, of a developer component compound, known for hair dyes, selected from the group consisting of aromatic polyfunctional amines having at least one primary amino group and at least one polyfunctional group in the ortho or para position and heteroaromatic amino compounds as well as the method of dyeing human hair utilizing said oxidation dyestuff combination of a developer component and a coupling component.

5 Claims, No Drawings

**METHOD AND COMPOSITIONS FOR THE DYEING
OF HUMAN HAIR**

THE PRIOR ART

The use of oxidation dyestuffs for dyeing human hair has been known for many years. The so-called developer components and coupling components are used for the production of the oxidation dyestuffs. It has already been suggested to use 3-amino-pyrazolones as coupling components and aromatic polyfunctional amines or 4-amino-pyrazolones as developer components. Good dyeing results can be achieved in many cases with these dyestuff combinations, which are transformed into dyes on the hair by oxidation either with air or particularly by the addition of chemical oxidants, like hydrogen peroxide. It was found, however, that the colors, particularly the yellow and brown shades, cannot be readily obtained by these oxidation dyestuff combinations.

OBJECTS OF THE INVENTION

An object of the present invention is, in an aqueous composition for dyeing human hair comprising an oxidation dyestuffs combination of a developer component and a coupling component and customary oxidation dyestuff adjuvants, the improvement which comprises utilizing as said oxidation dyestuff combination, (a) from 0.3 percent to 5 percent by weight of said composition, of a coupling component 3-amino-5-one having the formula

wherein R is selected from the group consisting of —N—H—CO—R₁, —NH—CO—NH—R₁ and —NH—C—S—NH—R₁, wherein R₁ is selected from the group consisting of alkyl having one to six carbon atoms, phenyl, halophenyl, alkylphenyl having 7 to 12 carbon atoms, alkoxyphenyl having 7 to 12 carbon atoms, dialkylaminophenyl having one to four carbon atoms in the alkyls, cyclohexyl, alkylcyclohexyl having 7 to 12 carbon atoms, pyridyl and piperidyl, and (b) from 0.3 percent to 5 percent by weight of said composition, of a developer component compound selected from the group consisting of (1) aromatic amines having the formulae

wherein R₂ is selected from the group consisting of OH, NH₂, NHR', and NR'', R' is selected from the group consisting of alkyl having one to four carbon atoms, hydroxylalkyl having one to four carbon atoms, phenyl and p-aminophenyl, and R₃ is selected from the group consisting of hydrogen, alkyl having one to four carbon

atoms, alkoxy having one to four carbon atoms, hydroxyl and amino, (2) 4-amino-pyrazolones having the formula

wherein R₄ is selected from the group consisting of hydrogen, alkyl having 1 to 10 carbon atoms, phenyl, p-aminophenyl, p-halophenyl, p-hydroxyphenyl, p-methylaminophenyl, p-dimethylaminophenyl, carboxyl, carbo-lower alkoxy, carbamoyl, —CONHR' and —CONR'', R' having the above assigned values, and R₅ is selected from the group consisting of hydrogen, alkyl having 1 to 10 carbon atoms, phenyl, alkylphenyl having 7 to 10 carbon atoms, alkoxyphenyl having 1 to 10 carbon atoms, aminophenyl-hydroxyphenyl, carboxyphenyl, carbamoylphenyl, sulfophenyl and aminosulfonylphenyl, and (3) amino-pyridines having the formula

wherein R₆ is selected from the group consisting of hydrogen, alkyl having one to four carbon atoms and phenyl.

Another object of the present invention is in the process of dyeing human hair which comprises treating the hair at temperatures of from 10°C to 40°C with an aqueous composition for dyeing human hair comprising an oxidation dyestuff combination of a developer component and a coupling component and customary dyestuff adjuvants, in the presence of an oxidizing agent, the improvement which comprises utilizing as said oxidation dyestuff combination, (a) from 0.3 percent to 5 percent by weight of said composition, of a coupling component 3-amino-pyrazol-5-one having the formula

wherein R is selected from the group consisting of —N—H—CO—R₁, —NH—CO—NH—R₁ and —NH—C—S—NH—R₁, wherein R₁ is selected from the group consisting of alkyl having one to six carbon atoms, phenyl, halophenyl, alkylphenyl having 7 to 12 carbon atoms, alkoxyphenyl having 7 to 12 carbon atoms, dialkylaminophenyl having one to four carbon atoms in the alkyls, cyclohexyl, alkylcyclohexyl having 7 to 12 carbon atoms, pyridyl and piperidyl, and (b) from 0.3 percent to 5 percent by weight of said composition, of a developer component compound selected from the group

consisting of (1) aromatic amines having the formulae

wherein R₂ is selected from the group consisting of OH, NH₂, NHR' and NR'₂, R' is selected from the group consisting of alkyl having one to four carbon atoms, hydroxyalkyl having one to four carbon atoms, phenyl and p-aminophenyl, and R₃ is selected from the group consisting of hydrogen, alkyl having one to four carbon atoms, alkoxy having one to four carbon atoms, hydroxyl and amino, (2) 4-amino-pyrazolones having the formula

wherein R₄ is selected from the group consisting of hydrogen, alkyl having 1 to 10 carbon atoms, phenyl, p-aminophenyl, p-halophenyl, p-hydroxyphenyl, p-methylaminophenyl, p-dimethylaminophenyl, carboxyl, carbo-lower alkoxy, carbamoyl, —CONHR' and —CONR'₂, R' having the above assigned values, and R₅ is selected from the group consisting of hydrogen, alkyl having 1 to 10 carbon atoms, phenyl, alkylphenyl having 7 to 10 carbon atoms, alkoxyphenyl having 1 to 10 carbon atoms, aminophenyl, hydroxyphenyl, carboxyphenyl, carbamoylphenyl, sulfophenyl and aminosulfonylphenyl, and (3) amino-pyridines having the formula

wherein R₆ is selected from the group consisting of hydrogen, alkyl having one to four carbon atoms and phenyl.

These and other objects of the invention will become more apparent as the description thereof proceeds.

DESCRIPTION OF THE INVENTION

The new method of dyeing human hair with solutions, emulsions or creams, which contain oxidation dyestuffs and other additives customary for hair dyes, is characterized in that the hair is treated in the presence of an oxidizing agent and at temperatures from 10°C to 40°C with 3-aminopyrazol-5-ones (coupling components) of the general formula I

wherein R represents —NH—CO—R₁ or —NH—CO—NH—R₁ or —NH—CS—NH—R₁ and R₁ denotes a hydrocarbon radical with 1 to 12 carbon atoms or a heterocyclic radical, and of developer components, known for hair dyes, based on aromatic di- or polyfunctional amines with at least one primary amino group as well as one additional functional group in para-position, or on heteroaromatic amino compounds.

The hydrocarbon radical R₁ can be present in the form of an aliphatic, aromatic or cyclo-aliphatic radical and also contain halogen atoms, particularly chlorine, or, in the case of cyclic compounds, alkyl- or alkoxy groups or dialkylamino groups with alkyl chains of one to four carbon atoms. Suitable heterocyclic radicals for R₁ are the pyridyl and piperidyl radicals.

In a preferred embodiment R₁ can be alkyl having one to six carbon atoms such as methyl, ethyl, isopropyl, n-propyl, n-butyl; phenyl; halophenyl such as p-chlorophenyl; alkylphenyl having from 7 to 12 carbon atoms such as p-methylphenyl, p-ethylphenyl, o-propylphenyl; alkoxyphenyl having from 7 to 12 carbon atoms such as o-methoxyphenyl, p-isopropoxyphenyl; dialkylaminophenyl having one to four carbon atoms in the alkyl such as p-dimethylaminophenyl; cyclohexyl; alkylcyclohexyl having from 7 to 12 carbon atoms such as methylcyclohexyl; pyridyl; and piperidyl.

Preferably 3-aminopyrazol-5-ones of the general formula II

II

are used as the coupling component compound where R₇ is alkyl having one to six carbon atoms.

As examples of readily available substituted 3-aminopyrazol-5-ones the following are mentioned:

1-phenyl-3-acetamido-pyrazol-5-one
 1-phenyl-3-benzamido-pyrazol-5-one
 1-phenyl-3-(3'-cyclohexylureido)-pyrazol-5-one
 1-phenyl-3-(3'-phenylureido)-pyrazol-5-one
 1-phenyl-3-(3'-p-chlorophenylureido)-pyrazol-5-one
 1-phenyl-3-(3'-ethyl-2'-thioureido)-pyrazol-5-one
 1-phenyl-3-(3'-n-butyl-2'-thioureido)-pyrazol-5-one
 1-phenyl-3-(3'-phenyl-2'-thioureido)-pyrazol-5-one
 1-phenyl-3-(3'-methylureido)-pyrazol-5-one
 1-phenyl-3-(3'-ethylureido)-pyrazol-5-one
 1-phenyl-3-(3'-n-propylureido)-pyrazol-5-one
 1-phenyl-3-(3'-isopropylureido)-pyrazol-5-one
 1-phenyl-3-(3'-n-butylureido)-pyrazol-5-one

The production of the substituted 3-aminopyrazol-5-ones used as coupling component compounds is effected according to known methods, such as reacting 3-aminopyrazol-5-ones with corresponding acyl chlorides, isocyanates or isothiocyanates in the presence of anhydrous aluminum chloride.

Suitable developer components are aromatic di-and polyfunctional amines with at least one primary amino groups as well as one additional functional group in the ortho or para, preferably the para position. Preferably these compounds are ortho or para aromatic diamines or hydroxyamines which can contain in addition other functional groups, such as $-\text{OH}$, $-\text{NH}_2$, $-\text{NHR}'$ and $-\text{N}(\text{R}')_2$. The preferred aromatic developer components of the aromatic amine type are aromatic amines having the formulae

wherein R_2 is selected from the group consisting of OH , NH_2 , NHR ; and NR'_2 , R' is selected from the group consisting of alkyl having one to four carbon atoms, hydroxyalkyl having one to four carbon atoms, a phenyl and p-aminophenyl.

Among compounds falling under the above formulae may be mentioned:

o-toluylene-diamine
o-phenylene-diamine
o-aminophenol
p-phenylene-diamine
p-toluylene-diamine
p-dimethylamino-aniline
p-aminophenol
p-diaminoanisol
p-aminodiphenylamine

As heteroaromatic amino compounds are used particularly 4-amino-pyrazolones as well as aminopyridines. Suitable 4-amino-pyrazolones which are preferably used are compounds of the general formula III:

III

wherein R_4 and R_5 are each, in general, hydrogen or an organic radical with 1 to 10 carbon atoms.

The organic radical R_4 of the 4-amino-pyrazolone can consist, for example, of an alkyl radical with 1 to 10 carbon atoms or of an aryl or heterocyclic radical. Furthermore, functional groups such as $-\text{OH}$, $-\text{NH}_2$, $-\text{NHCH}_3$, $-\text{N}(\text{CH}_3)_2$ or halogen atoms, particularly chlorine, can be present. Furthermore, suitable organic radicals are the following groups: $-\text{COOH}$, $-\text{COOR}'$, $-\text{CONHR}'$ and $-\text{CON}(\text{R}')_2$, where R' is lower alkyl or hydroxyalkyl with one to four carbon atoms.

The organic radical R_5 of the 4-amino-pyrazolone may be an alkyl radical of 1 to 10 carbon atoms or also an aryl or heterocyclic radical. Functional groups may further also be present. In particular, hydrocarbon radicals with 1 to 10 carbon atoms can be present which contain as functional groups $-\text{OH}$, $-\text{NH}_2$, $-\text{COOH}$, $-\text{CONH}_2$, $-\text{SO}_3\text{H}$ and $-\text{SO}_2\text{NH}_2$.

As an aromatic radical, in particular, phenyl is utilized for R_5 . The latter can contain alkyl- or hydroxyalkyl groups with one to four carbon atoms or other substituents, such as $-\text{NH}_2$, $-\text{OH}$, $-\text{COOH}$, $-\text{CONH}_2$, $-\text{SO}_3\text{H}$ or $-\text{SO}_2\text{NH}_2$.

Preferably in the above formula III, R_4 is selected from the group consisting of hydrogen, alkyl having 1 to 10 carbon atoms, phenyl, p-aminophenyl, p-halophenyl, p-hydroxyphenyl, p-methylaminophenyl, p-dimethylaminophenyl, carboxyl, carbo-lower alkoxy, $-\text{CONHR}'$ and $-\text{CONR}'_2$, R' having the above-assigned values, and R_5 is selected from the group consisting of hydrogen, alkyl having 1 to 10 carbon atoms, phenyl, alkylphenyl having 7 to 10 carbon atoms, alkoxyphenyl having 1 to 10 carbon atoms, aminophenyl, hydroxyphenyl, carboxyphenyl, carbamoylphenyl, sulfophenyl and aminosulfonylphenyl. Particularly suitable is 1-phenyl-3-carbamoyl-4-aminopyrazol-5-one.

It is frequently of advantage to use the 4-aminopyrazol-5-ones in the form of their salts with inorganic or organic acids, particularly hydrochloric or sulfuric acid, which reduces their sensitivity to air.

Suitable aminopyridines which can be utilized as developer component compounds are the aminopyridines having the formula

wherein R_6 is selected from the group consisting of hydrogen, alkyl having one to four carbon atoms and phenyl. Preferable are 2,5-diamino-pyridine and its substitution products, such as 2-dimethylamino-5-aminopyridine and 2-phenylamino-5-aminopyridine.

The dye formation can be represented by the following formulae, where 1-phenyl-3-carbamoyl-4-aminopyrazol-5-one is used as a developer component compound and 1-phenyl-3-(3'-methylureido)-pyrazolone as a coupling component compound.

YELLOW BROWN DYESTUFF

As with other oxidation dyestuffs, the colors can be developed both by atmospheric oxygen and by chemical oxidants. Preferably hydrogen peroxide or its addition products, like percarbamide, melamine perhydrate

and sodium perborate are used. The dyeing of the hair is effected at temperatures of 15° to 40°C, preferably at room temperature. The dye treatment of the living human hair is preferably for a period of 10 minutes to 1 hour followed by a rinsing of the hair.

The hair dyeing compositions may be applied in the form of aqueous solutions, but especially in the form of creams or emulsions. For this purpose, the developer and coupling component compounds are mixed with any optional wetting agents or washing compositions, especially anionic or non-ionic substances. Suitable wetting and washing agents are especially alkylbenzenesulfonates, fatty alcohol sulfates, alkylsulfonates, fatty acid ethanolamides, products of addition of ethylene oxide to higher alkyl amines and fatty alcohols, and fatty alcohol alkyl ether and polyalkyl ether sulfates.

The absorptive capacity of the above-mentioned dye-stuffs is also good when they are in admixture with such compositions. Consequently, the hair dyes can be produced in the form of shampoos, especially of cream shampoos, which are much desired in practice.

Further, thickeners such as, for example, methylcellulose, starch, higher fatty alcohols, vaselines, paraffin oil and fatty acids, and also perfume or hair conditioning substances such as, for example, pantothenic acid and cholesterol, may be admixed with the compositions of the invention.

The added substances are used in the amount customary for these purposes. Suitable added amounts of wetting agents are, especially, 0.5 percent to 30 percent by weight, and of thickeners, are 0.1 percent to 25 percent by weight, referred in each case to the total composition. The concentration of the dyestuff components (developer and coupling components) is to a certain extent dependent on the purpose of use and amounts, in each case, to 0.3 to 5 percent by weight, preferably 0.5 to 2.5 percent by weight. These quantities are also with reference to the total composition. 35 10

The hair dyes are adjusted so that they are alkaline, preferably to a pH value of 8 to 10. The dyeings obtained with the hair dyes described above have good properties with respect to light, washing and rubbing.

The present invention will be further described by way of reference to the following specific examples. These however are not to be deemed limitative of the practice of the invention.

EXAMPLE 1

2 Parts by weight of 1-phenyl-3-carbamoyl-4-aminopyrazol-5-one, $\frac{1}{2}$ H_2SO_4 , and 1.8 parts by weight

of 1-phenyl-3-(3'-methylureido)-pyrazol-5-one were dissolved in water containing ammonia and 5 parts by weight of ethanol. 50 Parts by weight of an emulsion formed from 10 parts by weight of a fatty alcohol (hydrocarbon chain length $C_{16}-C_{18}$), 26 parts by weight of sodium lauryl ether sulfate and 64 parts by weight of water were added thereto. The pH was adjusted to 9.5, 1 part by weight of hydrogen peroxide was added and the dye composition was made up to 100 parts by weight with water.

The dye cream so obtained dyed grey hair a yellow-brown when treated at room temperature over a period of 30 minutes. After the dye treatment, the hair was rinsed with water and shampooed.

EXAMPLE 2

2 Parts by weight of p-(2,5-diaminopyridine)-dihydrochloride and 2 parts by weight of 1-phenyl-3-(3'-ethylureido)-pyrazol-5-one were dissolved in water and worked into an emulsion as in Example 1. The mixture was adjusted to a pH of 9.5. 1 Part by weight of hydrogen peroxide was added and made up to 100 parts by weight with water.

The dye cream so obtained dyed grey hair a yellow brown when treated at room temperature over a period of 30 minutes. In place of hydrogen peroxide, equivalent amounts of melamine perhydrate, urea perhydrate or sodium perborate may be employed with comparable results.

EXAMPLE 3

Dye creams are produced as described in Example 1, but the compounds listed in the following Table I were used as developer and coupling components. Under similar conditions with a period of action of 25 minutes at a temperature of about 30°C, the dye colors indicated in the right column of the Table were obtained. The coupling components used correspond all to the general formula I.

For the sake of simplicity, Table I only indicated the group R.

When dyeing human hair, the hydrogen peroxide should preferably be added to the dye cream just prior to its application to the hair. While substantially equi-⁶⁵ molar amounts of the developer component and the coupling component have been utilized in the exam-

ples, other ratios such as 0.8 to 1.2 to 1 may be employed with comparable results.

The preceding specific embodiments are illustrative of the practice of the invention. It is to be understood, however, that other expedients known to those skilled

13

in the art may be employed without departing from the spirit of the invention or the scope of the appended claims.

I claim:

1. In the process of dyeing human hair which comprises applying to the hair at temperatures of from 10° to 40°C an effective amount of an aqueous composition for dyeing human hair comprising an oxidation dyestuff combination of a developer component and a coupling component at a pH from 8 to 10 in the presence of an oxidizing agent, the improvement which comprises utilizing as said oxidation dyestuff combination, (a) from 0.3 to 5 percent by weight of said composition, of a coupling component 3-amino-pyrazol-5-one having the formula

5
10

14

wherein R_1 is selected from the group consisting of alkyl having one to six carbon atoms, phenyl, halo-phenyl, and cyclohexyl, and (b) from 0.3 to 5 percent by weight of said composition, of a developer component compound selected from the group consisting of (1) an aromatic amine, (2) a 4-amino-pyrazolone, and (3) an amino-pyridine.

2. The process of claim 1 wherein said developer component and said coupling component are present in substantially equimolar amounts.

3. The process of claim 1 wherein said developer component compound is selected from the group consisting of 1-phenyl-3-carbamoyl-4-amino-pyrazol-5-one, p-toluylene-diamine, p-diaminoanisole, p-(N,N-dimethylamino)-aniline, p-aminodiphenylamine and 2,5-diaminopyridine.

4. The process of claim 1 wherein said developer component is said 4-amino-pyrazolone.

5. The process of claim 4 wherein said 4-amino-pyrazolone is 1-phenyl-3-carbamoyl-4-amino-pyrazol-5-one.
